CLAIM

The ornamental design for an adjustable bracket, as shown and described.

DESCRIPTION

FIG. 1 is a perspective view of an adjustable bracket showing my new design.

FIG. 2 is a top view of the adjustable bracket of FIG. 1; a bottom view of the adjustable bracket of FIG. 1 is the mirror image of FIG. 2.

FIG. 3 is a right side view of the adjustable bracket of FIG. 1.

FIG. 4 is a front view of the adjustable bracket of FIG. 1; a rear view of the adjustable bracket of FIG. 1 is the mirror image of FIG. 4.

FIG. 5 is a left side view of the adjustable bracket of FIG. 1.

FIG. 6 is an interior elevation view of the adjustable bracket of FIG. 1 along “Lines 6—6” of FIG. 2.

FIG. 7 is a perspective view of the right portion of the adjustable bracket of FIG. 1 in a sneeze guard hardware environment;

FIG. 8 is a perspective view of an embodiment the adjustable bracket of FIG. 1; and,

FIG. 9 is an exploded perspective view of an embodiment the adjustable bracket of FIG. 1.

The broken line showing of a partial pole is for illustrative purposes only and forms no part of the claimed design.
